McClelland Barclay, Los Angeles, Calif.

Application June 20, 1932. Serial No. 44,133

Term of patent 7 years

To all whom it may concern:

Be it known that I, McCLELLAND BARCLAY, a citizen of the United States, residing at Los Angeles, in the county of Los Angeles and State of California, have invented a new, original, and ornamental Design for a Combined Automobile Front Fender and Running Board, of which the following is a specification, reference being had to the accompanying drawings, forming a part thereof.

Fig. 1 is a side elevation of the combined automobile front fender and running board, a frag-

mentary portion of the figure being broken away for convenience of illustration.

Fig. 2 is a top plan view, with a fragmentary portion broken away for convenience of illustration, and

Fig. 3 is a perspective view showing the complete design.

I claim:

The ornamental design for a combined automobile front fender and running board, as shown.
